WILLIAM H. HUBBARD, OF WEST MERIDEN, CONNECTICUT, ASSIGNOR TO HIMSELF
AND JOHN HILL, OF SAME PLACE.

Letters Patent No. 88,715, dated April 6, 1869.

IMPROVED MATERIAL FOR PAINT.

The Schedule referred to in these Letters Patent and making part of the same.

To all whom it may concern:

Be it known that I, WILLIAM H. HUBBARD, of West Meriden, in the county of New Haven, and State of Connecticut, have invented a new Paint; and I do hereby declare the following to be a full, clear, and exact description of the same.

This invention has for its object a new paint which shall be very much cheaper than lead, yet possessing qualities of coloring in itself which lead does not; and

The invention consists in a new article of manufacture for paint, formed from peat, by drying and grinding into a powder, and then adding oil thereto, or not, as the case may be.

In order to the clear understanding of my invention, I will proceed to fully describe the same.

I take peat as it comes from the earth, and after thoroughly drying, I grind it to a powder, thus thoroughly combining and mixing all the vegetable and earthy matter contained in the peat. I then, in an ordinary paint-mill, grind the powdered peat with oil, when it is ready for use in like manner as lead and oil, the cost of the peat being comparatively nothing, and producing an article of nearly the same body as the lead.

From different soils, the peat obtained is a different color. In some cases, the finest possible black is obtained; in others, a red or reddish brown, but generally producing a beautiful madder brown.

Thus prepared, the paint is treated in like manner as lead and oil-paint, and possesses none of the poisonous, or injurious qualities of lead, an important feature, when the health of the painter is taken into consideration.

The peat, when thoroughly dried and ground becomes an article of manufacture, with or without oil, in like manner as ordinary white lead.

Having fully described my invention, What I claim as new and useful, and desire to secure by Letters Patent, is—

The herein-described paint, prepared by the process, substantially as set forth, as a new article of manufacture.

WM. H. HUBBARD.
